JEAN HUBERT LOUIS DE BATS, OF ZELIENOPLE, PENNSYLVANIA, ASSIGNEE, BY
MESNE ASSIGNMENTS, TO LAVA CRUCIBLE COMPANY OF PITTSBURGH, OF
PITTSBURGH, PENNSYLVANIA, A CORPORATION OF PENNSYLVANIA.

CRUCIBLE-FURNACE.

1,372,676.

Specification of Letters Patent. Patented Mar. 29, 1921.

Application filed March 3, 1917, Serial No. 152,430. Renewed August 5, 1920. Serial No. 401,565.

To all whom it may concern:

Be it known that I, JEAN HUBERT LOUIS De BATS, a resident of Zelienople, in the county of Butler and State of Pennsylvania, 5 have invented a new and useful Improvement in Crucible-Furnaces, of which the following is a specification.

This invention relates to so-called "crucible furnaces" in which metals are melted, refined or otherwise treated in pots or crucibles placed within the furnace. The object 10 of the invention is to provide a furnace of this kind which will conserve and extend the life of the crucible or pot; prevent oxidation and contamination of the metals being melted and treated, by the gases produced by the combustion of the fuel in the furnace; facilitate the removal of the crucible or pot and the replacement thereof in the furnace; 15 lessen the labor of supplying metals to the crucible or pot; and, when solid fuel is used, prevent waste of fuel, conserve the heat and lessen the labor necessary for cleaning and replenishing the fire.

20 In the accompanying drawings Figure 1 is a vertical section through the improved furnace, taken on line 1—1 Fig. 3; Fig. 2 is a plan view of the furnace; Fig. 3 is a horizontal section taken on line 3—3 Fig. 1; and 25 Fig. 4 is a sectional view of the grate bars on the line 4—4, Fig. 3.

The furnace comprises an outer chamber for containing the fire or fuel and a secondary chamber within the outer chamber 35 for containing the pot or crucible so that it is out of direct contact with the fire or flame.

As shown the furnace comprises an outer wall 1 built up of brick or other refractory material and inclosing the furnace chamber 2, and within said chamber is a wall 3 some 40 distance inwardly from the wall 1 to provide a space 4 for the fuel or fire, said wall 3 inclosing a crucible chamber 5 in which the crucible or pot 6 rests. The bottom of the chamber 2 is formed by a plate 7 upon which 45 wall 3 is erected and which plate 7, around the wall 3, is formed as a grate 8 for receiving coal, coke or other solid fuel. If desired, gas or liquid fuel burners may be applied 50 in the space 4. The outlet from the chamber 2 is through a side flue 9, through which the products of combustion are carried and conducted to a suitable stack or disposal medium, not shown. The top of the

furnace is provided with an opening or openings 10 through which the crucible is inserted and removed, and through which fuel is supplied to the furnace chamber 2.

The wall 3 will be built up of suitable heat conducting and refractory material, 60 and I have found that carbide of silica is suitable for this purpose, as it is not only strong and refractory but also a good conductor of heat. This wall is preferably built up in horizontal rings as shown in Fig. 1, 65 with adjacent faces of rings provided with interlocking means, such as a tongue fitting into a groove in the adjacent ring, to lock said rings together. The crucible 6 preferably is seated upon a suitable refractory 70 brick or block 12, which spaces the same from the bottom 13 of the crucible chamber.

In order to permit the ready cleaning of the fire, removal of clinkers and ash, and also to permit the ready repair of the supplementary wall 3, the bottom plate 7 is so mounted that it can be raised and lowered. To this end the furnace is supported on columns 14 resting on the foundation 15, four such columns being shown, and at their upper ends supporting an annular plate 16 on which the furnace walls 1 are erected, thus leaving an open space underneath the furnace. The bottom plate 7 is provided with 80 guide lugs 17 on two diametrically opposite 85 points, which engage two of the columns 14, to guide the plate 7 when being raised and lowered. Said bottom plate 7 is carried on the upper end of a lifting bar 18 which extends downwardly into a well 19 in the 90 foundation 15. This lifting bar will be adapted for a suitable jack, either hydraulic, pneumatic or mechanical, and as shown is a ratchet bar adapted for actuation by an ordinary ratchet jack, indicated 95 generally at 20, and which operates like any ordinary lifting jack for raising and lowering the bar 18 and with it the bottom plate 7.

The furnace walls are inclosed by a suitable steel shell 22 held by an up-turned 100 flange 23 on the bottom ring-plate 16, and a down-turned flange 24 on the top plate 25. This top plate is preferably a casting and forms the floor level of the furnace, and is preferably water-cooled by being provided 105 with cored-out passages or pipes 26 which lead out through the sides of the plate and have suitably connected thereto water supply

and waste pipes. The opening or openings 10 through the top of the furnace will of course be closed by a cover or covers as is usual in crucible furnaces.

5 In the use of the furnace, the crucible with its charge is placed within the chamber 5, resting upon the block 12, and the coke, coal or other fuel is supplied to the chamber 4 surrounding the crucible containing chamber. The draft is upwardly through the 10 grate 8 and the products of combustion are drawn out through the flue 9. Consequently the flame does not impinge against the crucible or pot, nor is the crucible or pot in contact with the fuel, receiving its heat purely 15 by conduction through the wall 3 and radiation in the chamber 5, giving a uniform heat throughout the crucible chamber. Since the 20 gases from the fire are drawn upwardly to the outlet flue 9, the material or metal in the crucible or pot will not be contaminated by these gases and will not be oxidized on its surface by any excess oxygen in these gases. To supply fuel to the chamber 4 a metal 25 cover will be lowered down through the opening in the top of the furnace, to cover the chamber 5* and thus allow fuel to be dumped in to fill the chamber 4. The crucible or pot will be placed in the chamber 5 30 and removed therefrom by means of suitable tongs in the usual manner, and because of the open space around the crucible or pot, the tongs can be made to engage the crucible or pot with ease and without danger of injuring the crucible.

When the fire is to be cleaned the jack 20 will be operated to lower the bottom plate 7 a few inches, thus allowing clinkers and ash to drop from the grate 8, after which the bottom plate 7 is again lifted. This cleaning 40 therefore can be effected very quickly and easily and without the necessity of poking, etc., as is necessary in ordinary crucible furnaces. Also, to make repairs or alterations 45 to the walls 3 the plate 7 will be lowered so that the entire wall construction 3 is below the normal grate level and as the furnace is entirely open underneath ready access is thereby had.

50 The furnace construction described has numerous advantages over crucible furnaces as ordinarily constructed, in which the crucible or pot rests within the furnace chamber proper and is surrounded or packed in the 55 burning coal or coke. Under ordinary practice the life of the crucible or pot is quite short, due to several causes or destructive agencies:

First: The crucible is subjected to excessive oxidation under a high heat, and as 60 these crucibles are formed of a mixture of graphite and clay the oxygen and heat have the effect of oxidizing the graphite on the outer surface of the crucible and producing 65 a vitreous or glazed condition of the clay, so

that the outer surface has a different coefficient of expansion and contraction than the body or inner portion of the walls. The depth of the glazed or vitreous portion increases with each heating, and because of the difference of expansion and contraction said glazed portion will spall or chip off, thus reducing the thickness of the crucible walls and soon leading to its entire destruction. With the improved furnace above described 70 the crucible is entirely protected from the oxygen and consequently there will be no oxidation or withdrawal of the graphite, the crucible walls tending to remain of the same composition or texture throughout, giving a 75 longer life.

Second: In the old practice the crucible is subjected to uneven temperatures on various parts thereof, no matter whether solid, gaseous or liquid fuel is employed, which is 80 liable to cause the crucible to crack and thus destroy the same. By having a crucible in the secondary chamber, as described, the heat is evenly diffused over the entire surface of the crucible, thus reducing its liability to 85 crack.

Third: Under the old practice the crucible is liable to mechanical injury due to being in direct contact with the solid fuel, which has hard sharp edges which may injure the outer 90 surface of the crucible, and particles of which are frequently crushed into the walls of the crucible by means of the tongs used to remove the pot, thus forming indentations in the crucible walls which soon burn entirely 95 through and thus destroy the crucible. Furthermore, to remove the crucible from the old style furnace it is necessary by means of a suitable instrument to poke downwardly 100 along the side of the pot at two opposite 105 points to provide spaces for the insertion of the tongs. The action of such tool frequently breaks or at least injures the crucible walls. All of these difficulties are overcome 110 by the furnace construction above described, as no fuel is in direct contact with the pot and sufficient space is left on the sides of the pot for the insertion of the tongs.

Fourth: Under present crucible use it is necessary to work over an open flame furnace when tamping down the fire to provide openings for the insertion of tongs and for this reason the workmen cannot guide the tools and frequently hit the crucible or pot and injure it, which is entirely avoided by the furnace construction described because the adjustment of the tongs to the crucible can be done so quickly that the workmen can do the same carefully.

Fifth: With the old furnace practice 125 there is a tendency of the solid fuel to fuse between the crucible and the block upon which it rests so that frequently the crucible is destroyed in an effort to remove it from the furnace. This is entirely avoided by the 130

furnace construction described above in that the pot rests upon a refractory block, out of contact with the fuel so that it is always perfectly free to be lifted when the charge is 5 completed.

For these reasons the furnace construction above described very greatly increases the life of the crucible or pots.

There is also a great saving in the fuel, 10 particularly when solid fuel is used. With the old furnace construction, inasmuch as the crucible or pot is practically embedded in the fuel, whenever it is removed the fuel falls down in the space occupied by the 15 crucible or pot, and before a new pot can be inserted a large part of this fuel must be poked down into the ash pit, so as to provide sufficient space for the new crucible or pot, after which a new supply of fuel must be 20 added to replace that which was poked down. This not only results in a waste of fuel, but the new fuel cools the furnace so that it requires considerable time to bring the furnace up to its heat and thus length- 25 ens the period of treating a crucible or pot of metal. With the new construction there is no waste of fuel whatsoever when one pot is removed and a new one put in, because the fuel is never in contact with the pot, and 30 furthermore, the temperature of the furnace is conserved and thereby the length of time of an individual heat is very greatly reduced.

With the furnace above described the fire 35 is much more quickly and economically cleaned than with the old furnace construction,—by merely lowering the furnace bottom and grate, as above described.

Another advantage of the new furnace 40 construction is the preservation of the purity of the metal being treated. The chief danger from impurities of any metal being treated in a crucible is due to the gases of combustion, which contain impurities. In 45 the old furnace constructions these pass directly over the open crucible or pot and contaminate the metal contained therein, and in addition they oxidize the metal to a considerable extent, thereby producing a waste 50 of metal and also preventing uniform results by changing the proportions of the mixtures and compositions of the metal. This is entirely overcome by the furnace construction described above, as the wall 3 55 inclosing the crucible directs the products of combustion upwardly so that the gas and oxygen do not come in contact with the surface of the metal being treated.

The secondary chamber in the furnace can 60 be readily and economically constructed and is formed by a strong but good heat conducting wall. When formed of carbid of silica it is very durable and not liable to fracture. It is built in a series of horizontal 65 rings and even if one ring should crack,

the crack is not liable to extend into adjacent rings, and should such a crack form in a ring the heat to which the same is subjected will again fuse the carbid of silica so as to close the crack. The interlocking of 70 the rings one with another, as described, will hold securely in place any cracked ring so that the inner wall will not break down, and requires only infrequent replacings.

What I claim is:

1. A crucible furnace comprising a main furnace chamber, a bottom therefor arranged to be lowered and lifted, and a crucible containing chamber erected on said bottom, the walls of said crucible chamber 80 being imperforate and formed of refractory heat-conducting material and rising from the furnace bottom and spaced from the walls of the main chamber to provide a space for the fire therebetween, said crucible chamber being wider than the crucible 85 to permit the latter being inserted and removed by means of tongs.

2. A crucible furnace comprising a main furnace chamber and a crucible containing chamber within said main chamber, the walls of said crucible chamber being imperforate and formed of carbid of silica and rising from the furnace bottom and spaced from the walls of the main chamber 95 to provide a space for the fire therebetween, said crucible chamber being wider than the crucible to permit the latter being inserted and removed by means of tongs.

3. A crucible furnace comprising a main 100 furnace chamber, a bottom therefor arranged to be lowered and lifted, and a crucible containing chamber erected on said bottom, the walls of said crucible chamber being imperforate and formed by horizontal 105 rings of refractory heat-conducting material and rising from the furnace bottom and spaced from the walls of the main chamber to provide a space for the fire therebetween, said crucible chamber being wider than the 110 crucible to permit the latter being inserted and removed by means of tongs.

4. A crucible furnace comprising a main furnace chamber and a crucible containing chamber within said main chamber, the 115 walls of said crucible chamber being imperforate and formed of horizontal interlocking rings of refractory heat-conducting material and rising from the furnace bottom and spaced from the walls of the main chamber to provide a space for the fire therebetween, said crucible chamber being wider than the crucible to permit the latter being inserted 120 and removed by means of tongs.

5. A crucible furnace comprising a main furnace chamber, a bottom therefor arranged to be lowered and lifted, and a crucible containing chamber formed by refractory heat conducting walls erected on said 130

bottom and rising therefrom and spaced from the walls of the main chamber to provide a space for the fire therebetween, said crucible chamber being wider than the crucible to permit the latter to be inserted and removed by means of tongs, and a grate forming the bottom of the space surrounding said crucible containing chamber.

6. A crucible furnace comprising a main furnace chamber, a bottom therefor arranged to be lowered and lifted, and a crucible containing chamber supported on said bottom and formed by refractory walls located within said furnace chamber and spaced from the walls thereof to provide a space for the fire exteriorly of said crucible containing chamber, and a grate forming the bottom for the space between the walls

of the main chamber and the crucible chamber.

7. A crucible furnace comprising a main furnace chamber, a bottom therefor arranged to be lowered and lifted and formed as a grate around its peripheral portion, and a crucible containing chamber on the central portion of said bottom and formed of refractory good heat conducting walls and providing a space for the fire there-around.

In testimony whereof I have hereunto set my hand.

JEAN HUBERT LOUIS DE BATS.
